GEOMETRICAL INSTRUMENT

Paul Asperger, Flint, Mich.

Application September 22, 1955, Serial No. 535,925

8 Claims. (Cl. 33—158)

This invention relates to geometrical instruments, and more particularly, to trammel head-like constructions for use, either singularly or in pairs, upon beams, the blades of squares, rules, or other straightedges for providing compasses, dividers, calipers, or different types of gauges.

The main object of the present invention is to provide a novel and improved head unit of the character indicated, which is slidably adjustable upon a blade or rule-like beam, and which has detachably associated therewith either a scribing or a measuring attachment with one end of each attachment readable with calibrations on the blade or rule and with the other end constructed for marking or measuring distances between two points.

Another object of the invention is to provide in a device of the character set forth, a novel clamping construction for adjustably, rigidly, and accurately attaching trammel heads upon a blade or rule-like beam.

A further object of the invention is to provide, in a device of the character indicated, a novel construction whereby a single pair of caliper legs attached to a pair of trammel heads and aligned with graduations on a blade or rule-like beam can be used for both inside and outside measurements.

It is also an object of the invention to provide a device of the above-indicated character which is simple and substantial in construction, economical to manufacture, and thoroughly efficient and practical in use.

These, together with various auxiliary features and objects of the invention which will later become apparent as the following description proceeds, are attained by the present invention, a preferred embodiment of which has been illustrated, by way of example only, in the accompanying drawings, wherein:

Figure 1 is a front elevation of a pair of the improved trammel heads attached to a calibrated blade of a square for use of the device as a compass or dividers;

Figure 2 is a rear elevation of one of the trammel heads showing the same attached to a portion of a square blade;

Figure 3 is an end view of the same;

Figure 4 is an enlarged vertical section taken on line 4—4 of Figure 1;

Figure 5 is also an enlarged sectional view, but is taken on line 5—5 of Figure 4;

Figure 6 is an enlarged fragmentary front elevation showing a caliper leg attached to a trammel head which has been broken away; and

Figure 7 is a vertical section taken on line 7—7 of Figure 6.

Referring now more specifically to the accompanying drawing wherein like numerals designate similar parts throughout the various views, the numeral 10 indicates generally a detachable blade of a machinist's square having on opposite sides and along both longitudinal edges thereof graduations 11. While the blade of a machinist's square is shown for the purpose of illustration, it is to be understood that the member 10 may be a steel rule or any other type of straightedge having flat sides, parallel edges,

2

and of a thickness similar to that of a square blade or steel rule.

The improved trammel head forming the subject matter of this invention has a main body member 12 which is substantially C-shaped consisting of a straight and relatively long bight portion 13 and short upper and lower parallel arms 14 and 15, respectively, which are also straight and are joined to said bight portion with sharp right-angle corners. The inner surfaces of the arms 14 and 15 are spaced apart a distance substantially equivalent to, but slightly in excess of, the width of the blade 10 so that said blade may be received between the spaced arms 14 and 15 and be embraced by said bight portion 13 and arms 14 and 15. Extending entirely through the lower arm 15 and parallel with the bight portion 13 is a bore 16 into which an indicator leg 17 is received and held in place by a set screw 18. The indicator leg 17 has a pointer 19 on its lower end and another pointer 20 on its upper end. Also the upper end of the indicator leg 17 is cut away to provide a flat surface 21, which is in surface engagement with a side of the blade 10 at graduations 11 along one edge of said blade. It will be observed in Figure 4 of the drawings that one side of the blade 10 is in surface engagement with the bight portion 13 of the body member, the opposite edges of the blade 10 are in close proximity to the inner side of the arms 14 and 15, and the flat 21 on the indicator leg is in surface engagement with the side of the blade 10 opposite to that engaged and embraced by the bight portion 13.

The upper arm 14 is entirely bifurcated, as at 22, and receives in said bifurcation one leg 23 of a substantially L-shaped clamping member 24, said clamping member being pivotally mounted on and carried by the body member 12 by a pair of aligned pivot pins 25 threaded in the forked portions of the arm 14 and having tapered inner ends 26 thereof received in like-shaped recesses in opposite sides of the leg 23 of said clamping member. The other leg 27 of the clamping member extends downwardly in rear of the bight portion 13 of the body member 12 and has a thumb screw 28 threaded therethrough that engages the rear side of the bight portion 13 for forcing the leg 23 downwardly and into engagement with the upper edge of the blade 10 upon inward threading movement of the thumb screw 28. It will be observed by referring to Figure 4 that the undersurface 29 of the leg 23, when in engagement with an edge of the blade 10, is at a slight acute and undercut angle to the surface along the edge of the blade 10 for holding said blade 10 back and against the bight portion 13.

The leg 23 of the clamping member 24 has a threaded opening 30 extending downwardly therein into which is threaded the lower end of a post 31 onto which is rotatably mounted a finger-gripping knob 32 for convenient manipulation of the device when used for any of the purposes above-designated. It will be further observed that when the surface 29 of the leg 23 of the clamping member 24 is in clamping engagement with an edge of the blade 10, the post 31 and the axes of the finger-engaging knob 32 are in direct alignment with the indicator leg 17.

In Figures 6 and 7, there is shown an indicator leg 17^a which has the upper portion thereof constructed identical to that of the indicator leg 17, but has substantially the lower half thereof reversely bent, as at 17^b, with the pointer 19^a thereof slightly rounded and in direct alignment with an imaginary straight line along the center line of the upper pointer 28 and tangent at the pointer 19^a. Indicator legs of this character used upon a pair of trammel heads clamped to a blade or rule-like straightedge provide both inside and outside beam calipers, and the change from one to the other only requires transferring the trammel heads to opposite ends of the rule-like beam.

When adjusting the trammel head along the rule-like beam, the thumb screw 28 is loosened to relieve locking pressure on the edges of said beam, and because of the construction and arrangement of the upper end of the indicator leg 17 and close association of the bight portion 13 and both arms 14 and 15 with said beam, said body member is slidably retained on and relative to said beam. When clamping the trammel head in adjusted position, the angled undercut lower surface 29 of the leg 23 of the clamping member 24 not only clamps on the edges of the beam, but also forces and holds the bight portion of the body member in surface frictional contact with a side of the rule-like beam.

From the foregoing description, it can be seen that there is provided a trammel head and indicator attachments thereto for use, either singularly or in pairs, upon a rule-like beam to provide a beam compass, beam dividers, beam calipers, or as either a height gauge or a surface gauge.

In view of the above description, taken in conjunction with the accompanying drawings, it is believed that a clear understanding of the construction, operation, and advantages of the improved trammel head will be quite apparent to those skilled in this art. A more detailed description is accordingly deemed unnecessary.

It is to be understood, however, that even though there is herein shown and described a preferred embodiment of the invention, various changes may be made without departing from the spirit and full intentment of the invention.

What is claimed is:

1. A trammel head comprising, in combination with a stiff rule-like beam, a substantially C-shaped body member closely embracing one side and opposite edges of said rule-like beam with its bight portion and the spaced arms respectively, said arms of said C-shaped body member having their free ends extended beyond the opposite side of said rule-like beam and one arm being provided with a bore therethrough that is parallel with the bight portion of said body member and has the center thereof spaced from the inner embracing surface of said bight portion substantially the thickness of said rule-like beam, an indicator leg positioned in said bore and having a flat on a side and at one end thereof, said flat being in surface engagement with the side of said rule-like beam opposite to that embraced by said bight portion, attaching means for detachably supporting said leg in said bore, and a clamp movably mounted at and relative to the other arm of said C-shaped body and arranged to apply pressure on the edge of said rule-like beam adjacent thereto and thereby force the opposite edge of said rule-like beam against and in frictional contact with the first-mentioned arm.

2. A device as defined in claim 1 wherein said rule-like beam has graduations along edges thereof and wherein said end of said leg having said flat is also tapered to a point and is registerable with graduations on said rule-like beam.

3. A trammel head comprising, in combination with a stiff rule-like beam having graduations along edges thereof, a substantially C-shaped body member closely embracing one side and opposite edges of said rule-like beam with its bight portion and the spaced arms respectively, said arms of said C-shaped body member having their free ends extended beyond the opposite side of said rule-like beam and one arm being bifurcated while the other is provided with a bore therethrough that is parallel with the bight portion of said body member, an indicator leg positioned in said bore and having a flat on a side and at one end thereof, said flat being in surface engagement with the side of said rule-like beam opposite to that embraced by said bight portion, a set screw for detachably supporting said leg in said bore, and a clamp member pivotally mounted in the bifurcated arm of said C-shaped body member and arranged for applying pressure on the

edge of said rule-like beam adjacent thereto upon movement on its pivot and thereby force the opposite edge of said rule-like beam against and in frictional contact with the first-mentioned arm.

5. A trammel head comprising, in combination with a stiff rule-like beam having graduations along edges thereof, a substantially C-shaped body member closely embracing one side and opposite edges of said rule-like beam with its bight portion and the spaced arms respectively, said arms of said C-shaped body member having their free ends extended beyond the opposite side of said rule-like beam and one arm being bifurcated while the other is provided with a bore therethrough that is parallel with the bight portion of said body member, an indicator leg positioned in said bore and having a flat on a side and at one end thereof that is in surface engagement with the side of said rule-like beam opposite to that embraced by said bight portion, a set screw for detachably supporting said leg in said bore, a clamping member pivotally mounted in the bifurcated arm and engageable with the edge of the rule-like beam adjacent thereto, and a thumb screw threaded through said clamping member and engaging said body member for moving said clamping member on its pivot and into engagement with said edge of said rule-like beam.

15 6. A device as defined in claim 4, wherein a rotatable finger-gripping knob is provided on the pivoted clamping member and is offset therefrom in a direction opposite to that in which said leg extends for convenient manipulation of the device.

20 7. A trammel head comprising, in combination with a stiff rule-like beam having graduations along edges thereof, a shouldered body member slidably along said rule-like beam and closely embracing one side and one edge of said rule-like beam, a clamping member movably mounted on said body member and arranged for applying frictional pressure on the edge of said rule-like beam opposite to that embraced by said body member for holding said body member against movement relative to said rule-like beam, an indicator leg detachably carried by said body member at a location adjacent embracement thereof with an edge of said rule-like beam, a flat on a side and at an end of said indicator leg, said flat being in surface engagement with the side of said rule-like beam opposite to that embraced by said body member, and a pointer on each end of said indicator leg, said pointer on the end of said leg having said flat being registerable with the graduations on said rule-like beam.

25 8. A device as defined in claim 6, wherein the indicator leg is reversely bent at a location outwardly of its attachment to the body member and wherein an imaginary straight line along the center line of the pointer at the graduations and tangent at the pointer at the end of said reversely bent end portion is at right angles to the edges of the rule-like beam.

30 9. A trammel head comprising, in combination with a stiff rule-like beam having graduations along edges thereof, a substantially C-shaped body member closely embracing one side and opposite edges of said rule-like beam with the bight portion and the spaced arms thereof respectively, said arms of said C-shaped body having their free ends extended beyond the opposite side of said rule-like beam and one arm being bifurcated while the other is provided with a bore therethrough that is parallel with the bight portion of said body, an indicator leg attached in said bore and registerable with the graduations on the rule-like beam, said indicator leg having a flat on its side at one end thereof that is in surface engagement with the side of said rule-like beam opposite to that embraced by said bight portion, a substantially L-shaped clamping member pivotally mounted in the bifurcated arm and having a flat surface on one leg thereof that is engageable with the edge of the rule-like beam adjacent thereto, and a thumb screw threaded in the other leg of said clamping member and engaging said body

member for moving said clamping member on its pivot to bring said flat surface on said clamping member into engagement with the edge of said rule-like beam, said flat surface on said clamping member being at a slight acute and undercut angle to the surface along the edge of the rule-like beam when said clamping member is rotated to a position where it is in clamping engagement with said edge. 5
